United States Patent Office

Des. 199,505
Patented Nov. 3, 1964

199,505

STORAGE CONTAINER FOR LIQUIDS

James B. Swett, 8 Devonshire Drive, Barrington, R.I.,
and Henry J. Marien, 46 N. Country Club Drive, War-
wick, R.I.

Filed Apr. 25, 1963, Ser. No. 74,615

Term of patent 14 years

(Cl. D58—17)

FIG. 3

FIG. 4

FIG. 6

FIG. 5

FIG. 7

FIGURE 1 is a perspective view of a storage container for liquids showing our new design;

FIGURE 2 is an end elevation view thereof;

FIGURE 3 is a top plan view thereof;

FIGURE 4 is a bottom plan view thereof;

FIGURE 5 is an end elevation view thereof, viewed from the end opposite that shown in FIGURE 2;

FIGURE 6 is a cross section taken on line 6—6 of FIGURE 1; and

FIGURE 7 is a cross section taken on line 7—7 of FIGURE 1.

The side opposite to that shown in FIGURE 1 is a mirror image thereof.

We claim:

The ornamental design for a storage container for liquids, as shown and described.
